STEAM TRAP

Hans Richter, Bremen, Germany

Application November 5, 1937, Serial No. 172,964
In Germany November 6, 1936

2 Claims. (Cl. 137—103)

This invention relates to steam traps and the like and more particularly to a float controlled device for draining condensation water and air from steam heating plants, cooking utensils and the like.

One of the primary objects of the invention is to provide a steam trap of the type indicated of simple and economical construction which will drain the condensation water and the imprisoned air effectively without loss of steam.

A further object is to provide a steam trap which will permit convenient inspection of the condensate at all times.

Other objects and advantages will become apparent as the specification proceeds and when taken in connection with the accompanying drawings which illustrate a preferred embodiment of the inventive concept together with possible modifications thereof.

20 In the drawings:

Figure 1 is a cross section of a steam trap according to the invention.

Figure 2 is a section along the line 2—2 of Figure 1.

Figure 3 is a section along the line 3—3 of Figure 1.

Figure 4 is a modified construction.

Figure 5 is a section along the line 5—5 of Figure 4.

Figure 6 is still another modification.

Figure 7 is a modified valve construction according to the invention and

Figure 8 is another modified valve construction.

As previously stated the instant invention relates to a steam trap in which the drainage valve is controlled by means of a float. This float mechanism is in turn actuated by the condensation water in the steam trap. Thus, if the level of the condensation water drops to minimum the drainage valve will be closed. When the level rises on the other hand, the float mechanism will operate to open the valve to drain the condensate. However, the considerable loss of steam during the draining in the steam traps heretofore used has presented a serious problem. Attempts have been made to prevent the escape of steam during the drainage by keeping the water level slightly above the drainage opening even when the float is in its lowest position, that is, when the valve is fully closed.

Investigations have shown, however, that despite this arrangement the strong current occasioned by the discharge of the condensation water produces a vortex or a whirl somewhat similar to a water spout, the velocity of which is propor-

tional to the pressure of the discharge water and the cross section of the drainage opening. This whirl or spout in turn produces a suction through the water which will draw also live steam through the drainage opening. This phenomenon accounts for the considerable loss of live steam.

The purpose of the present invention is to isolate this whirl formed during the discharge of the condensation water from the live steam so that only water and imprisoned air will be drained from the trap.

Referring to the embodiment of the invention disclosed in detail in the drawings, the novel steam trap comprises a steam chamber 10 into which the live steam is conducted through the opening 11. The condensation water is drained through the drainage opening 12 and into the drainage conduit 13. The drainage opening 12 is opened and closed by the valve 14 which in turn is controlled by the float 15 having a lever 16 connected with a crank shaft 17 which opens and closes the valve 14.

It will be noticed that the device is so constructed that the water level will be above the level of the drainage opening even when the float 15 is in its lowest position in the steam chamber.

The drainage opening and the valve is isolated from the live steam by means of the hood 18 which encloses entirely the drainage opening and the valve and extends towards the vicinity of the float 15. This hood 18 is provided with an opening 19 adjacent the floor of the steam chamber 10. This opening is preferably wide horizontally and narrow in height so that that part of the hood facing the float 15 will be covered by the sealing liquid even when the float is in its lowest position. Because of the partial vacuum produced during the drainage operation the water will be at a higher level within the hood 18 than in the steam chamber proper.

When the water level rises by virtue of the condensation of the steam, the float 15 will open the valve 14. The current produced by the drainage through the drainage opening 15 and the conduit 13 will produce a whirl 25. Under ordinary circumstances this whirl would also suck out the steam in the steam chamber 10 but, by virtue of the isolating hood 18, only the trapped air within the hood will escape which is one of the desired purposes of the steam trap.

Because of the wide opening 19 of the hood, the velocity of the current at this point is practically nil and, consequently, no whirl is formed. However, for the sake of precaution a baffle 20 is provided on the hood in order to prevent the

water level from dropping too rapidly should vacuum be produced despite the low velocity of the current.

In the modification illustrated in Figure 4, the lever 21 instead of being arranged along the side of the hood 22, is bent at 23 through the opening 19. This lever may be connected to the valve 14 in the same manner as the lever 16 in the modification shown in Figure 1.

10 A baffle 24 is provided on the hood for the same purpose as the baffle 20 in the modification shown in Figure 1, but is preferably slotted to accommodate the lever 21.

The hood 22 in this modification is integral 15 with the walls of the steam chamber 10. Thus, the whirl 25 can be observed through the windows 26. The different reflection of light by water and air will make the whirl, which ordinarily is colorless, visible through these windows.

20 Thus, it may be ascertained at any time whether there is air within the hood 22 and whether this air is sucked out of the whirl. The windows are preferably extended vertically but narrow horizontally so that the whirling current may be observed through its entire length.

In the modification illustrated in Figure 6, the hood and float mechanism is arranged similar to Figure 1. The valve 30, however, is of the reciprocating type and is provided with a strainer 30 or screen 27 which serves to distribute the current over a greater area. Thus, the formation of one strong whirl or spout will be prevented and instead there will be a plurality of currents. The lever 31 is provided with a slotted link 32 engaging the shaft 33.

Figure 7 shows a different kind of a current distributor 28 and Figure 8 shows a ball chamber 29 which may be arranged immediately above the drainage opening. This ball chamber will 40 split up the whirl into a plurality of irregular partial whirls.

These current distributors, although not essential to the operation of the mechanism are desirable in order to relieve tension on the isolating hood, particularly when the operating pressure is high and when the discharge opening is comparatively large.

It will be understood that the specific illustra-

tions shown have been given by way of example and not by way of limitation and these structures are naturally subject to wide variation and modification without departing from the scope of the invention. Thus, the isolating hood may be given a different form and the current distributors may embody a great variety of constructions.

I claim:

1. A steam trap construction comprising a casing 10 having an inlet for live steam and an outlet for condensation water and a valve for controlling said outlet, said outlet being disposed in the floor of said casing, a space in said casing 15 extending below the level of said outlet, a partition forming a chamber within said casing extending over and above said outlet and said valve and downward into said water collecting space but spaced from the floor thereof to form an opening for admission of water into said chamber, said opening being larger in cross section than said outlet opening whereby whirls during the draining operation will be prevented, and float controlled means in said casing for maintaining the level of the condensation water above said opening, whereby said chamber will be isolated from the steam and escape of steam through said outlet will be prevented.

2. A steam trap construction comprising a 20 casing having an inlet for live steam and an outlet for condensation water and a valve for controlling said outlet, said outlet being disposed in the floor of said casing, a space in said casing for collecting the condensation water, said space 25 extending below the level of said outlet, a partition forming a chamber within said casing extending over and above said outlet and said valve and downward into said water collecting space but spaced from the floor thereof to form an opening for admission of water into said chamber, said opening being larger in cross-section than said outlet opening whereby whirls during the draining operation will be prevented, and means connected with said valve for controlling the 30 same.

HANS RICHTER.
